UNITED STATES PATENT OFFICE.

RALPH W. SHAFOR, OF DENVER, COLORADO, ASSIGNOR TO THE DORR COMPANY, A CORPORATION OF DELAWARE.

MIXING APPARATUS.

1,364,412.

Specification of Letters Patent. Patented Jan. 4, 1921.

Application filed July 26, 1916. Serial No. 111,380.

To all whom it may concern:

Be it known that I, RALPH W. SHAFOR, a citizen of the United States, residing at Denver, in the county of Denver and State 5 of Colorado, have invented certain new and useful Improvements in Mixing Apparatus, of which the following is a specification.

This invention relates to apparatus for mixing a gas with a liquid or semi-liquid 10 in the production of chemical compounds.

My invention is particularly adapted for use in the manufacture of sodium bicarbonate (NaHCO_3) by the ammonia soda process, and in this connection provides an efficient substitute for what is commonly 15 known as the carbonating tower.

The primary object of my invention is to provide an apparatus which operates to agitate a liquid or semi-liquid by means of and 20 in the presence of a gas or a mixture of gases at any required pressure either above, at, or below atmospheric and to the exclusion of other gases.

With this object in view, my invention 25 consists of an air-tight container provided with inlet openings for a liquid or semi-liquid and a gas with which the latter is to be mixed and saturated, and with discharge openings for the surplus gas and the 30 compound-product of the process.

Rotatably mounted adjacent the bottom of the tank is a mechanism for moving the settling precipitates toward the ingress opening of an air-lift which operates by injection of the gas used in producing the 35 compound.

The egress opening of the lift delivers in 40 a plurality of distribution troughs which rotate in conjunction with the impelling mechanism and which distribute the raised matter uniformly over the surface of the liquid in the tank.

To obtain a uniform feed, despite possible pressure variations inside the container, either a pump of definite displacement is employed or the liquor to be treated is admitted to the container past a regulatable automatic pressure-valve from a constant head.

50 The conduit connected with the discharge opening of the tank is sealed and provided with an automatic check valve to prevent the inflow of air at this point.

By adjustment of the valves and possible 55 variation in the feed head, the feed and discharge can be varied in accordance with the

predetermined pressure under which the mixing process is carried on within the container.

The gas with which the liquid or semi-liquid is mixed and saturated is introduced 60 into the ingress opening of the before referred to lift by means of a nozzle which connects with a compressor.

The surplus gas discharged from the tank 65 is preferably returned to this compressor and a regulatable pressure-valve is placed between the compressor and the source of gas supply with which it connects for the purpose of automatically regulating the 70 supply of gas according to the difference in pressure of the gas in the said source and the pressure at which it is admitted to the container.

By the above described system of coöperative devices, the gas is in the operation 75 of my improved apparatus, circulated in a closed system and it is introduced into the tank at a constant predetermined pressure and is maintained at the same pressure 80 throughout the mixing process.

Containers of the hereinbefore described construction may be used in series for the repeated treatment of the product of the process until a compound of the desired proportions is obtained.

In connecting the containers in a series, the discharge outlet of each unit, with the exception of the last one, connects with the feed opening of the next adjoining unit and 90 the gas-feed nozzles and surplus gas-nozzles of the different containers are connected by means of manifolds with the compressor.

When my improved mixing apparatus is used in the manufacture of sodium bicarbonate, (NaHCO_3) a brine solution (NaCl) saturated with ammonia gas (NH_3) is fed 95 into the container in the manner hereinbefore described, and carbon dioxid gas (CO_2) is introduced into the lift which operates to agitate and circulate the ingredients until the one is thoroughly saturated with the other.

The excess dioxid gas with perhaps a small amount of ammonia escapes from the 105 container and is returned to the compressor or conveyed to a storage tank, and the product of the operation, sodium bicarbonate, is discharged either into a storage tank or into another container in which it is 110 brought into intermixture with a fresh supply of dioxid gas.

It will be readily understood by those versed in the art to which my invention appertains that in the operation of my improved apparatus a more thorough intermixing of a liquid or a liquid and solids in suspension with a gas, or a mixture of gases is obtained than is possible in the use of a carbonating tower of the usual construction, that the cost of installation and expenses of operation are greatly reduced, that the absorption of the gas by the liquids is more thorough and uniform, and that the operation may be carried on under any desired pressure either below, at or above atmospheric.

In the accompanying drawings in the various views of which like parts are similarly designated,

Figure 1 represents a sectional elevation of my improved apparatus in its operative condition,

Fig. 2, a plan view of the apparatus shown in Fig. 1, part of the top of the container having been broken away to reveal the mechanism within the same,

Fig. 3, a sectional elevation of a plurality of containers of my invention connected in a series for the repeated treatment of the materials to be intermixed, and

Fig. 4, a sectional elevation showing the application of my invention to a tank of the Pachuca type.

Referring more specifically to the drawings, the reference numeral 2 designates a preferably cylindrical tank or mixing vat made of steel or other suitable material and closed to provide an air-tight container.

Rotatably suspended from a supporting structure 3 mounted on top of the tank, is a shaft 4 which extends through a stuffing box 5, centrally within the same.

An open-ended tubular conduit 6 secured at the lower end of the shaft, extends in the vertical axis of the tank with its ends separated from the top and bottom surfaces of the same to provide for the ingress and egress of circulating matter.

The shaft carries a plurality of radially extending troughs 7 which communicate with the egress opening at the upper end of the conduit and which are provided with a number of outlets 8 for the distribution of matter over the surface of the liquid contents of the tank.

The rotating tubular conduit carries at its lower end a plurality of radial arms 9 provided with obliquely disposed, transverse scraper-blades 10 which move solids which in the process settle to the bottom of the tank, toward the center of the same.

A nozzle 12 fitted in a central opening in the bottom of the tank extends into the lower open end of the tubular conduit and connects exteriorly of the tank, with a compressor 13.

The compressor is fed from a conveniently located source of gas-supply 14 through a system of connected pipes which includes a branch 15 connected with an opening 16 in the top of the tank to receive the surplus gas exhausted therefrom.

An automatic spring-regulated pressure valve 17 is connected in the pipe system between the source 14 and a point at which the branch 15 is connected therein, to maintain the gas within the tank at the pressure at which it is admitted thereto.

This pressure is varied in accordance with the character of the compound to be produced and is regulated by adjustment of the spring of the valve to a resistance substantially equal to the difference between the required pressure in the tank and the pressure in the source of gas supply.

The liquid or semi-liquid which forms one of the ingredients of the compound is admitted to the tank at a point below a determinate liquid level through a valve-controlled pipe 18 which at its upper end connects with a supply tank 19 having an overflow 20 to provide a head of constant pressure.

Instead of employing the tank 19, any other equivalent element may of course be used.

The compound-product of the mixing process carried on in the tank is discharged therefrom by means of a pipe 21, the outer end of which is sealed against the entrance of air, by any suitable means such as its submergence in the liquid contents of a receptacle 22 provided with an overflow 23.

The end of the pipe within the tank is preferably turned downwardly below the liquid level, as shown at 24 in Fig. 1 to prevent the escape of free gases with the mixture.

An automatic pressure valve is connected in the pipe 21 as at 25 to prevent the flow of liquid into the tank when the pressure within the same is below atmospheric.

In the operation of my invention, a liquid or a liquid and solids in suspension, and a gas or a mixture of gases at the required pressure, are admitted to the tank through the pipes connecting with the supply tank 19 and the conveying system of which the source of gas supply 14 and the compressor 13, form part.

The liquid mass in the tank is constantly maintained on a level established by the position of the discharge pipe 21 and indicated in Fig. 1 of the drawings by the broken line 26.

A slow rotary movement is imparted to the shaft 4 by means of a gearing 27 at its upper end, the arms 9 are in consequence moved across the bottom surface of the tank and their obliquely disposed blades impel the settling precipitates toward a central

point beneath the ingress opening at the lower end of the tubular conduit 6 at which the arms are attached.

The gas injected through the nozzle 12 lifts the solids and liquids through the conduit to the egress opening at the upper end thereof and compels their discharge into the distributing troughs 7 which by their rotary movement in conjunction with the conduit, uniformly distribute the raised matter over

the surface of the liquid in the tank.

The gas, liquid and solids in suspension are thus constantly circulated within the tank and thoroughly intermixed and the resultant compound is discharged from the tank through the pipe 21.

It will be understood without further explanation that the arrangement of the inlet-conduits with relation to the sources of supply, the seal which protects the discharge pipe, and the regulatable automatic pressure valves conjointly prevent the inflow of gases other than that fed through the nozzle 13, and permit of gases being admitted and maintained at any desired pressure either below, at or above atmospheric.

The surplus gas escaping from the tank through the opening 16 mixes with that drawn from the source of supply 14 by the compressor 13.

In case of incomplete saturation of the liquid with the gas, the discharge of the tank may be mixed with a fresh supply of gas as often as required, by connecting two or more of the tanks in a series as illustrated in Fig. 3 of the drawings.

The discharge pipe of each tank, with the exception of that of the last tank of the series, connects with the inlet opening 40 of the next adjoining tank which to this end is placed at a lower elevation and the nozzles 12 and the gas-escape openings 16 of the several tanks, connect with the compressor through the intermediary of manifolds 28 and 29.

In Fig. 4 of the drawings, my invention has been illustrated in connection with a tank of the Pachuca type. The air-conduit 6 is in this form of my invention fixed within a closed container 30 provided with a sloping bottom, and the sweeps 10, the distributing troughs 7, and the operating mechanism, shown in Fig. 1, are eliminated.

What I claim and desire to secure by Letters-Patent is:

1. Apparatus for producing a gas-and-liquid compound comprising a closed container provided between the top and bottom with an outlet for the compound product establishing a liquid level and an upper gas space, a source of liquid supply having an inlet connected with the container below the liquid level, a vertical conduit mounted within the container and extending from the lower portion thereof to a

point above the liquid level and provided at its upper portion with a nozzle discharging into the lower end of the vertical conduit and forming a gas lift, pressure producing means located between the nozzle 70 and the source of gas supply and a return conduit extending from the gas space of the container and connected with the gas supply between the same and the pressure producing means.

75

2. Apparatus for producing a gas-and-liquid compound, comprising an airtight container provided between the top and bottom with an outlet for the compound product establishing a liquid level and an upper gas space, a source of liquid supply having an inlet connected with container below the liquid level, a vertical rotary conduit mounted within the container and extending from below a lower portion thereof to a point above the liquid level and provided at the top with outlets and having means operating in the gas space for discharging the liquid at intervals and for distributing the discharged liquid over the surface of the liquid within the container, a source of gas supply having a nozzle discharging into the lower end of the vertical conduit to form a gas lift, a pump connected with the gas supply for forcing the gas 95 under pressure through the said nozzle, and a return conduit connected with the gas space and with the gas supply between the same and the pump.

95

3. Apparatus for producing a gas-and-liquid compound comprising a closed container provided between the top and bottom with an outlet for the compound product establishing the liquid level and an upper gas space, a source of liquid supply having an inlet pipe connected with the container below the liquid level, a vertical rotary conduit tube suspended from the top of the container and extending from the lower portion of the same to a point above 110 the liquid level and provided within the gas space with outlets and having liquid distributing means arranged to discharge liquid at intervals and distributing the discharged liquid over the surface of the liquid 115 within the container and a gas supply having a nozzle extending through the bottom of the container and projecting into the lower end of the conduit to form a gas lift, a pump connected with the gas supply 120 for forcing the gas under pressure through the nozzle and a return pipe connecting the gas space with the gas supply between the latter and the pump.

115

In testimony whereof I have affixed my 125 signature in presence of two witnesses.
